UNITED STATES PATENT OFFICE.

FURNEY F. GREEN, OF COALGATE, OKLAHOMA.

TIRE.

1,162,350.

Specification of Letters Patent. Patented Nov. 30, 1915.

Application filed October 17, 1914. Serial No. 867,082.

To all whom it may concern:

Be it known that I, FURNEY F. GREEN, a citizen of the United States, residing at Coalgate, in the county of Coal and State of Oklahoma, have invented a new and useful 5 Tire, of which the following is a specification.

The device forming the subject matter of this application is a resilient tire and one 10 object of the invention is to provide a novel form of casing.

Another object of the invention is to provide a structure of the type above mentioned in which the casing cooperates in a novel 15 manner with the side walls of the rim band.

A further object of the invention is to provide novel means for preventing a creeping 20 of the casing upon or with respect to the rim band.

It is within the scope of the invention to improve generally and to enhance the utility 25 of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawings:—Figure 1 shows in side elevation, a portion of a 40 wheel to which a tire constructed in accordance with the present invention has been attached, parts being shown in section; Fig. 2 is a transverse section of the structure shown in Fig. 1; Fig. 3 is a fragmental side elevation showing a portion of the rim band and the inner strip, the casing being removed; Fig. 4 is a fragmental longitudinal section taken through the cooperating anti-creeping 45 elements; Fig. 5 is a composite perspective showing one form of means whereby the constituent segments of the rim band may be connected together; Fig. 6 is a fragmental side elevation of a wheel to which a modified form of the invention has been applied, portions being sectioned; Fig. 7 is a 50 transverse section of that form of the invention depicted in Fig. 6; Fig. 8 is a fragmental longitudinal section of the device delineated in Fig. 6, Fig. 8 disclosing the anti-creeping means; Fig. 9 is a composite per-

spective showing a modified means whereby the constituent segments of the rim band may be united; Fig. 10 is a side elevation showing a modified form of anti-creeping 60 means, parts being broken away; Fig. 11 is a cross section of the structure shown in Fig. 10; Fig. 12 is a fragmental longitudinal section showing the structure of Fig. 10.

In carrying out the present invention and referring particularly to Figs. 1, 2, 3 and 4, the invention is shown as comprising a felly 1 circumscribed by a rim band 2. The rim band 2 preferably is fashioned from metal and is provided upon its under face, as shown in Fig. 1, with transverse lugs 3 received in transverse recesses in the felly 1. The function of the lugs 3 is to prevent rim band 2 from creeping circumferentially on the felly 1. The rim band 2 comprises side walls 4, the outer faces of which slant, or converge from each other as they extend toward the felly 1. The rim band 2 may be composed of any desired number of segments 6, as shown in Figs. 5 and 9. In order to connect the ends of the segments 6 of the rim band, the same may be provided with cooperating knuckles 7 as shown in Fig. 5, the knuckles receiving connecting pins or bolts 8. However, if desired, and as shown in Fig. 9, openings 9 may be formed in one segment of the rim band adjacent its end, the openings 9 being adapted to receive tongues 10 struck from the other segment of the rim band. The side walls 4 of the rim band 2 are provided at intervals with notches 11.

When the invention is embodied in pneumatic form there is employed a tube 12 inflated by means of a valve 14 extended through the felly 1. Interposed between the tube 12 and the rim band 2 is a trough-shaped, resilient, metallic, inner strip 15 which rests immediately upon the rim band 2.

The invention includes an outer, metallic trough-shaped strip 16 provided along its longitudinal edges with hook-shaped beads 23 defining flanges 17. The strip 16 may be resilient if desired, to the end that it may flatten slightly in its tread portion. The flanges 17 are equipped with laterally extended projections 18 received in the notches 11 of the side walls 4 of the rim band 1. As shown in Fig. 4, the projections 18 may be of flared form and when this construction is employed, the edges of the notches 11 are

beveled as indicated at 19 in Fig. 3. The function of the parts 18 and 11 is to prevent the outer strip 16 and the casing (to be described hereinafter) from creeping with respect to the rim band 2.

The casing 20 is fashioned from rubber, canvas, or a combination of these materials as is common in the art and is carried by the strip 16. In practical operation, the casing 20 is built up upon the strip 16 and is firmly attached thereto by cementing or otherwise. The strip 16 is not attached to the tube 12. The longitudinal edges of the casing 20 are grooved as shown at 21 to define an inner wing 22 and an outer wing 24. The flange 17 enters the groove 21 and the inner wing 22 is firmly bound between the flange 17 and the body portion of the strip 16. The outer wing 24, however, is free and is adapted to reciprocate upon the inclined face 5 of the side wall 4 when the casing 20 and the tube 12 are compressed.

Referring to Figs. 6, 7 and 8, wherein a modified form of the invention is shown, the 25 felly is denoted by the numeral 25 and the rim band is shown at 26. The rim band 26 is provided upon its inner face with transverse lugs 39, corresponding to the lugs 3 of Fig. 1 and received in the transverse grooves 30 in the felly 25, to the end that the rim band may not creep circumferentially on the felly. The side walls of the rim band 26 are shown at 27 and the outer faces 28 of the side walls are inclined, as described in connection with 35 the faces 5 of the side walls 4, and for a like purpose. The inner, trough-like metallic strip is shown at 29 and is equipped with a hook-shaped bead 30 defining a flange 31. The strip 29 is attached firmly to the casing 40 32 and the latter is grooved as shown at 33 to receive the flanges 31, the inner wings 34 and the outer wings 35 being of the form hereinbefore described and having the functions hereinbefore set forth so far as the 45 bead 30 and the inclined face 28 are concerned.

In the place of the anti-creeping means 18—11 hereinbefore set forth, tongues 36 are struck laterally from the flanges 31 and 50 tongues 37 are struck from the side walls 27 of the rim band 26. The tongues 36 and 37 interengage, as clearly shown in Fig. 8, to prevent the casing 32 and attendant parts from creeping on the rim band 26. The 55 tongues 36 project in opposite directions and the tongues 37 are shaped accordingly. Therefore, the casing 32 and attendant parts cannot creep in either direction, circumferentially of the rim band.

60 In the form under discussion, helical springs 38 are connected one end to the rim band or bear loosely thereon, as may be found expedient. The springs 38 are of conical form, the smallest, terminal convolutions of the springs 38 terminating in fin-

gers 40, passing through the metallic strip 29 and entering the tread portion of the casing 32. Although the casing 32 ordinarily is secured so firmly to the strip 29 that relative movement between these parts is impossible, it will be observed that the fingers 40 aid in preventing relative movement between the casing and the strip 29. Conversely, the strip 29 forms a firm place of attachment for the fingers 40 and prevents the casing 32 from being worn by the movement of the outer ends of the springs.

The anti-creeping means 18—11 of Fig. 3 is applicable to that form of the invention which is disclosed in Fig. 7; and the anti-creeping means shown in Fig. 8 may be employed in that form of the invention shown in Fig. 2.

In Figs. 11, 10 and 12, a modified form of anti-creeping means is shown and this 85 form may be used with the construction shown in Fig. 1 or with the construction shown in Fig. 6.

In Figs. 11, 10 and 12, the felly is shown at 41 and the rim band at 42. Relative movement between these parts is prevented as before, by means of the lugs shown at 3 and 39 as hereinbefore described. The side walls of the rim band are shown at 43 and the outer faces of the side walls are inclined as shown at 44 for the purpose hereinbefore set forth. The outer, metallic band is shown at 45 and corresponds to the bands or strips 29 and 16. The hook-shaped beads are shown at 46, the same defining flanges 47. Referring to Fig. 10, the beads 46 are notched to define shoulders 48. In the rim band 42 at the sides of the felly 41, openings 49 are formed. Into the openings 49 project bends or projections 50 formed upon the intermediate portions of anti-creeping elements, the anti-creeping elements embodying arms 51 terminally engaged with the shoulders 48. The anti-creeping elements are resilient.

Having thus described the invention, what is claimed is:

1. In a device of the class described, a rim band embodying side walls; and a casing provided along its edges with inner wings and outer resilient wings which are independent of the inner wings, the inner wings lying between the side walls, and the outer wings engaging the outer faces of the side walls slidably, the outer faces of the side walls diverging from their outer edges toward their inner edges to increase the frictional hold of the outer wings on the side walls when the casing is compressed and when the outer wings slide upon the side walls.
2. In a device of the class described, a rim band having side walls; a casing; and a metallic outer strip fitted into the casing and provided along its edges with hook-shaped

- beads extended around the edges of the casing and defining flanges which bear slidably upon the side walls; and anticreeping means forming an operative connection between the 5 strip and the rim band.
3. In a device of the class described, a rim band having side walls; a casing having grooves in its edges defining inner and outer wings; a metallic strip fitting in the casing 10 and provided along its edges with hook-shaped beads extended around the edges of the inner wings and defining flanges lying against the outer faces of the inner wings, the flanges being slidably engaged with the inner faces of the side walls, the side walls entering the grooves, and the outer wings being slidably engaged with the outer faces of the side walls.
4. In a device of the class described, a rim 20 band having side walls; a casing having grooves in its edges defining inner wings and outer resilient wings; a metallic strip fitting in the casing and provided along its edges with hook-shaped beads extended around the 25 edges of the inner wings and defining flanges lying against the outer faces of the inner wings, the flanges being slidably engaged with the inner faces of the side walls, the side walls entering the grooves, and the outer resilient wings being slidably engaged 30 with the outer faces of the side walls, the outer faces of the side walls being inclined to increase the frictional hold of the outer wings upon the walls when the casing is compressed and when the outer wings slide upon the walls.
5. In a device of the class described, a rim band having side walls; a casing having grooves in its edges defining inner wings and outer resilient wings; a metallic strip fitting 40 in the casing and provided along its edges with hook-shaped beads extended around the edge of the inner wings and defining flanges lying against the outer faces of the inner wings, the flanges being slidably engaged with the inner faces of the side walls, the side walls entering the grooves, and the outer resilient wings being slidably engaged 45 with the outer faces of the side walls, the outer faces of the side walls being inclined to increase the frictional hold of the outer wings upon the walls when the casing is compressed and when the outer wings slide upon the walls; and anti-creeping means forming an operative connection between 50 the strip and the rim band.

In testimony that I claim the foregoing as my own, I have hereto affixed my signature in the presence of two witnesses.

FURNEY F. GREEN.
